CLAIM

The ornamental design for packaging for cigarette packs, boxed articles or playing cards, as shown and described.

DESCRIPTION

FIG. 1 is a left front perspective view of the packaging for cigarette packs, boxed articles or playing cards showing our new design;

FIG. 2 is a top view thereof;

FIG. 3 is front side view thereof; and,

FIG. 4 is a left end view thereof.

The broken lines shown in the drawing are included for the purpose of illustrating features of the packaging for cigarette packs, boxed articles or playing cards that form no part of the claimed design.

The rear, bottom and right views are not part of the claimed design.
